(57) **CLAIM**

The ornamental design for a training apparatus, as shown and described.

DESCRIPTION

FIG. 1 is a front, bottom, and right side perspective view of a training apparatus showing my new design.

FIG. 2 is a front elevational view thereof.

FIG. 3 is a right side elevational view thereof, the left side elevational view being a mirror image thereof.

FIG. 4 is a top plan view thereof.

FIG. 5 is a bottom plan view thereof.

FIG. 6 is a rear elevational view thereof, the patterns of hexagonal shapes being surface ornamentation which is flat.

FIG. 7 is a rear elevational view thereof, the patterns of hexagonal shapes being surface pattern which is flat; and, FIG. 8 is a cross-sectional view thereof, taken along line 8a,b,c,-8a,b,c,d in FIG. 7.
